UNITED STATES PATENT OFFICE.

ALEXANDER McPHADEN, OF CHICAGO, ILLINOIS, ASSIGNOR OF ONE-HALF TO EDWARD K. AANONSEN AND ONE-HALF TO JOSEPH T. SANDBERG, BOTH OF CHICAGO, ILLINOIS.

DESIGN FOR A POCKET DEPOSIT-RECEPTACLE.

50,842.

Specification for Design.

Patented May 29, 1917.

Application filed December 7, 1916. Serial No. 135,705. Term of patent 3½ years.

To all whom it may concern:

Be it known that I, ALEXANDER McPHADEN, a subject of the King of England, residing at Chicago, in the county of Cook and State of Illinois, have invented a new, original, and ornamental Design for Pocket Deposit-Receptacles, of which the following is a specification, reference being had to the accompanying drawing, in which—

Figure 1 is an elevation of a deposit receptacle illustrating my new design. Fig. 2 is a perspective view thereof, and Fig. 3 is a side elevation.

I claim:

The ornamental design for a pocket deposit receptacle as shown.

ALEXANDER McPHADEN.
